SEAL

Leslie A. Buell, Holly, Mich.

Application April 25, 1940, Serial No. 331,649

8 Claims. (Cl. 292—317)

This invention relates to an improved construction of seal, and more particularly to an improved construction of seal of the type generally used in sealing freight car doors.

- 5 More particularly, it is an object of this invention to provide a seal, of the above referred to type, of simple construction and a few parts to thereby provide a seal which may be manufactured at a very low cost.
- 10 Still another aim of the invention is to provide an improved seal wherein the looped portion of the strap, adjacent one of its ends, is provided with a frangible portion located on the outer side of the seal or casing and which will be ruptured if an attempt is made to force the seal and which will be so positioned that the frangible portion will be clearly visible to indicate that the seal has been tampered with, thereby avoiding the possibility of the seal being forced open and then arranged to give the appearance that the seal is still intact.
- 15 Other objects and advantages of the invention will hereinafter become more fully apparent from the following description of the drawing, which 20 illustrate a preferred embodiment thereof, and wherein:

Figure 1 is a top plan view showing the seal locked.

Figure 2 is an enlarged fragmentary horizontal 30 sectional view of the same, taken substantially through the center of the seal or casing and showing the strap end when in a partially locked position.

Figure 3 is a view similar to Figure 2 showing 35 the strap end in a fully locked position.

Figure 4 is a longitudinal vertical sectional view 40 taken substantially along the plane of the line 4—4 of Figure 2.

Figure 5 is a transverse vertical sectional view 45 taken substantially along the plane of the line 5—5 of Figure 1, and

Figure 6 is a top plan view showing the blank 50 from which the strap is formed.

Referring more particularly to the drawing, 55 wherein like reference characters designate like or corresponding parts throughout the different views, 10 designates generally the car door seal which includes generally a strap designated 11, and casing or seal designated 12.

50 The strap 11, as best seen in Figure 6 is formed from a strip of relatively thin, flexible metal and includes an enlarged disk shaped end 13 which is cut along the spaced lines 14 from its outer end to adjacent its inner end to form a struck-out portion or tongue 15. Adjacent the disk 13, the strap 11 is provided with an enlarged portion 16 along a portion of one of its longitudinal edges, such enlargement being provided with an elongated opening 17. The opposite edge of the strap 11 is provided with a notch 18 which is dis-

posed in transverse alignment with the opening 17, for a purpose which will hereinafter become apparent. The strap 11 is provided with a restricted portion 19, provided with an opening 20, adjacent that portion of the strap which is provided with enlargement 16. The opening 20 and the restricted portion 19 combine to form a frangible section 21, for a purpose which will hereinafter become apparent. Adjacent its opposite end the strap 11 is provided with an elongated opening 22 and an opening 23 between the opening 22 and the intermediate portion of the strap 11.

The tongue or struck-out portion 15 is shaped, as seen in Figure 2, being bowed outwardly relatively to the disk 13 with its free end extending through the opening 24 formed by the tongue 15 in the disk 13. Intermediate of its ends the tongue or struck-out portion 15 is provided with a folded portion forming a lug or stop 25 which extends inwardly of the tongue 15 and obliquely toward its secured end and which extends to but not through the opening 24, as seen in Figure 2.

The enlargement 16 is adapted to be folded 25 along the line 26 which is parallel to the longitudinal edges of the strap 11 and which intersects the opening 17 intermediate of its ends to position portion 16 in spaced apart, substantially parallel relationship to the contiguous portion of 30 the strap 11 to form a slotted passage 27 therebetween, as best seen in Figures 2, 3 and 5. When thus folded, the opening 17 forms a notch corresponding to the notch 18.

The casing or seal 21 is substantially spherical 35 shaped and is formed of the sections 28 and 29, each of which is substantially hemispherical. The sections 28 and 29 have their edges bent to provide outwardly off-set inwardly opening channel portions 30 and 31, respectively, which extend substantially three-quarters of the way around said edges. The channel portion 30 is adapted to receive the edge of the disk 13 and the channel portion 31, which is larger than the channel portion 30, is adapted to fit thereover 45 and be clamped thereto to form the crimped joint 32 for connecting the sections 28 and 29 to form the seal or casing 12. Between the ends of the joint 32, the edges of the sections 28 and 29 are provided with opposed cut-out portions forming an opening 33 for receiving the enlargement 16 and the contiguous portion of the strap 11. The portions of the seal 12 which define the ends of the openings 33 are disposed in the notches 17 and 18 for securely fixing the seal or casing 12 55 on the disk end 13 of the strap 11, with the tongue or struck-out portion 15 disposed in the seal 12 and forming a resilient latch element, as will hereinafter be described. When the casing or seal 12 is thus assembled on the disk end 13 of 60

the strap 11, said end forms the secured end of the strap, and the opposite end thereof, which is provided with the opening 22, constitutes the free end of the strap, designated 34, which is 5 adapted to be passed through the slotted passage 21 and into the casing or seal 12 along the side of the disk 13 opposite to that on which is disposed the latch element 15. As the end 34 is advanced into the seal 12 its leading end engages and retracts the free end of the latch element 15 causing it to retract to permit the end 10 34 to pass and be held thereby in a retracted position until the opening 22 is in position to receive it at which time it is projected, due to its 15 resiliency, through said opening 22 and into the position, as seen in Figure 2. The end 34 is then retracted relatively to the seal 12 causing the latch element 15 to be drawn through the opening 22 and into the position, as seen in Figure 3, 20 for securely connecting the ends of the strap 11 to thereby form the loop 35 in the intermediate portion thereof. If an attempt is made to release the end 34 to open the seal, as by passing a blade through the passage 21 between the ends of 25 the strap 11 for retracting the latch element 15, the leading end of the blade will contact the stop 25 which projects toward the slotted passage 21 and which will therefore prevent the latch element 15 from being retracted in this manner. 30 If an attempt is made to force the seal by pulling outwardly on the end 34 the frangible portion 21 will be ruptured at a point where said rupture will be clearly visible thereby preventing a rupture at a point within the casing 12 which might 35 be concealed by returning the end 34 into the casing leaving it loosely disposed therein. When the seal is locked, as in Figures 1 and 3, the opening 20 alines with the opening 23 so that these portions of the strap can be connected by 40 a seal, not shown, such as a wire passed therethrough with the ends twisted and enclosed in a lead seal.

As the seal 10, like all seals of its type, is destroyed when opened, the seal is only intended 45 and adapted to be used once and it is therefore necessary to provide a construction that can be manufactured as reasonable as possible and this result is accomplished by forming the latch element or tongue 15 integral with the strap 11 thereby greatly reducing the expense of manufacture.

Various modifications and changes are contemplated and may obviously be resorted to as only a preferred embodiment of the invention 55 has been disclosed.

I claim as my invention:

1. A seal comprising an elongated strap, a casing secured to and enclosing one end of said strap, said end having an elongated struck-out portion forming a slot in the strap, said struck-out portion forming an arcuately shaped spring latch, the free end of said latch extending through the slot in said strap, said housing having an opening to receive the opposite end of the strap, and said last mentioned end having an opening to receive the free end of said latch for connecting the ends of the strap.
2. A seal as in claim 1 said latch being folded upon itself, intermediate of its ends, to form a lug to be drawn through the opening in the last mentioned end of the strap, when said end is retracted relatively to the casing to form a stop

to prevent an implement being inserted into the housing, between the strap ends, for retracting the latch element.

3. A seal comprising a strap having an enlarged end provided with an integral struck-out strip forming a slot in said end, a casing enclosing said end, and provided with an opening through which the strap projects, said struck-out strip being arcuately shaped and being disposed with its free end projecting through the slot of said enlarged end, and the opposite, free end of the strap being insertable through the opening in the casing for engaging and retracting the free end of said strip relative to the slot, the free end of the strap having an opening to receive the free end of said strip, when the free end of the strap is fully inserted in the casing, for connecting the strap ends.

4. A car door seal comprising an elongated strap having an enlarged disk shaped end provided with an integral elongated strip struck out from said disk shaped end and forming a slot therein, said strip being bowed relatively to the plane of said end and disposed on one side thereof to form a latch element, said latch element having its free end projecting through said slot, said strap having a laterally enlarged portion adjacent its disk shaped end, said laterally enlarged portion being folded back onto the contiguous portion of the strap to form a passage therebetween to receive the opposite end of the strap, said opposite end having an opening to receive the free end of the latch member when the free end of the strap is inserted through said passage, and a seal secured to and enclosing said disk shaped end and said latch element.

5. A car door seal as in claim 4, said seal being formed of hemispherical sections having an inwardly opening channel shaped joint for receiving the marginal edge of said disk shaped end for positioning said end relatively to the seal.

6. A car door seal as in claim 4, said latch element being folded upon itself, intermediate of its ends, to form a lug, said lug projecting from the inner side of said latch element and obliquely toward its secured end to provide a stop to prevent insertion of an instrument between the ends of the strap for retracting the latch element.

7. In a car door seal, an elongated flexible strap, a seal secured to and enclosing one end of said strap and provided with an opening in which a portion of the strap, adjacent said end, is disposed, the enclosed end of said strap being provided with an integral resilient latch element, said latch element being bowed outwardly relatively to one side of said enclosed end, and having its free end extending across the plane of the enclosed end of said strap, the opposite, free end of the strap being provided with an opening and being insertable through the opening of said seal and on the opposite side of said enclosed end for retracting the free end of the latch element and for positioning its opening to receive the latch element for connecting the ends of the strap.

8. A car door seal as in claim 7, said latch element having a stop, intermediate of its ends, projecting from its inner side and toward its secured end, to prevent an instrument being inserted between the ends of the strap for retracting the latch element out of engagement with the opening in the free end of the strap.
